UNITED STATES PATENT OFFICE.

ANDREW NICOLL, OF NEWARK, NEW JERSEY.

GIRTH FOR HARNESS.

No. 919,063.

Specification of Letters Patent. Patented April 20, 1909.

Application filed September 19, 1908. Serial No. 453,845.

To all whom it may concern:

Be it known that I, ANDREW NICOLL, a citizen of the United States, residing at Newark, in the county of Essex and State of New Jersey, have invented certain new and useful Improvements in Girths for Harness; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in harness; and, the invention has reference, more particularly, to a novel form and construction of girth for use with the saddle of the harness, the girth being constructed with a view of preventing the chafing or galling of the horse at those points where the front legs of a horse join into the fore-shoulders, or what are sometimes termed the "arms" of the horse.

The present invention, therefore, has for its principal object to provide a simple and novel construction of girth which is of especial benefit in its use as a part of the harness for fast running horses or colts having a large motion or throwing of the legs, thus causing the fore-legs of the horse to be constantly brought in rubbing contact with the girth, as ordinarily made, and thus very often resulting in producing a sore or chafed condition of the arm-portions of the legs, especially during hot weather.

Other objects of this invention will be clearly understood from the following detailed description of my present invention.

With the objects of my present invention in view, the same consists, primarily, in the novel girth for harness hereinafter set forth; and, the invention consists, furthermore, in the various novel arrangements and combinations of parts, all of which will be more fully described in the following detailed description of the invention and then finally embodied in the clauses of the claims which

are appended to and which form an essential part of this specification.

The invention is clearly illustrated in the accompanying drawings, in which:—

Figures 1 and 2 are the two face views of a girth embodying the principles of my present invention; Fig. 2 showing one of the straps 55 for attaching the girth to a harness-saddle broken away. Fig. 3 is an end-elevation of the various parts represented in said Fig. 2. Fig. 4 is a side view of the girth, said view being made on an enlarged scale, showing portions of the girth-straps. Fig. 5 is a transverse vertical section, said section being represented as taken on line 5—5 in said Fig. 2, but said section being made on an enlarged scale; and Fig. 6 is a detail horizontal section 60 representation of the one end-portion of the girth, said section being represented as taken on line 6—6 in Fig. 3 of the drawings, and said section being made on an enlarged scale.

Similar characters of reference are employed in all of the above described views, to indicate corresponding parts.

Referring now to the several figures of the drawings, the reference-character A indicates the girth embodying the principles of the present invention, the same comprising an inner reinforcing or stiffening member or element 1, usually made of metal, but any other suitable material may be used, as will be clearly evident. This member or element 1, as clearly indicated in the dotted outline in Figs. 1 and 2 of the drawings, is made of the peculiar sinusoidal configuration shown, so as to provide a member having the main centrally disposed marginal edge-portions 2 and 3, the concave marginal edge-portion 4, and the convex marginal edge-portions 5 located upon opposite sides of the edge-portions 2 and 3 and directly back of a plane passing through the marginal edge-portion 3 and at right angles to the plane of either face-portion of the member or element 1 located between said marginal edge-portions 2 and 3, substantially as illustrated. The said element or member 1 terminates

also in substantially short end-portions 6 and 7, as shown. This said reinforcing or stiffening element or member 1, which is of a concavo-convex conformation, when viewed 5 from the side, as shown in Fig. 3 of the drawings, so as to be properly placed upon the under side of the body of a horse, is suitably incased in a casing made of leather, or other suitably soft and flexible material, which consists essentially of an outer facing 8, and an inner facing 10 adapted to be placed against the body of the horse. The inner facing 10 has its marginal edge-portions 11 doubled over upon themselves, so that said doubled-over 15 edge-portions will abut against the marginal edge-portions of the said reinforcing or stiffening member or element 1, and the marginal edge-portions 12 of the outer facing 8 resting directly upon the doubled-over edge-portions 11 of the inner facing, as clearly illustrated in said Fig. 5 of the drawings, the said facings being permanently secured together by means of the stitching 13 sewed through the said registering marginal edge-portions. 20 The inner facing 10 is arranged upon the said reinforcing or stiffening member or element 1 in such a manner, as to provide a suitably chambered space between the parts, which is stuffed with a suitable padding, 25 as 14.

Suitably secured upon the respective end-portions of the girth, thus produced, are buckles 15 for suitable attachment of the girth to the usual straps of the saddle. A 30 flexible pad or member 16 may also be attached to the outer face of the inner facing 10, as shown, and acts as a cushion or pad which rests against the under portion of the body of the horse to prevent chafing, as will be 35 clearly evident.

The reference-character 17 indicates a suitable girth-strap or runner which is loosely arranged and held in place by loops 18 attached to the outer face 9 at the points indicated 45 more particularly in Figs. 2 and 4 of the drawings, the said strap or runner 18 having secured to its respective end-portions suitable strap-members 19 and buckles 20, to which may be attached in the usual manner 50 the free end-portions of said straps which are provided with the buckle-tongue receiving holes or perforations 21.

From an inspection of Figs. 1 and 2 of the drawings, it will be seen, that I have provided 55 a harness-girth of a concavo-convex configuration, when viewed from the side, so as to conform to the curvature of the body of the animal, and when viewed from the top or bottom, the girth being of a sinusoidal configuration, comprising a forwardly extending and centrally disposed portion, with two concave portions in which the upper portions or "arms" of the front legs of the horse can 60 freely move, while running, without any pos-

sibility of any parts of the legs being brought 65 in rubbing contact with the edges of the girth, so that all danger of chafing or galling is clearly overcome; and, a girth is the result, which when placed upon the horse is of the greatest comfort to the animal, while running, and also allows of the free use of the legs in throwing or moving them back and forth, as will be clearly evident.

I claim:

1. A girth for harness comprising a concavo-convex stiffening member, and a casing of a soft and flexible material surrounding said stiffening member, said casing comprising an outer and an inner facing, and a padding between said inner facing and one side 80 of said stiffening member, substantially as and for the purposes set forth. 75

2. A girth for harness comprising a concavo-convex stiffening member, and a casing of a soft and flexible material surrounding said stiffening member, and buckles at the respective ends of said casing for attachment thereto of the ends of the saddle-straps, substantially as and for the purposes set forth. 85

3. A girth for harness comprising a concavo-convex stiffening member, and a casing of a soft and flexible material surrounding said stiffening member, and buckles at the respective ends of said casing for attachment thereto of the ends of the saddle-straps, said casing comprising an outer and an inner facing, and a padding between said inner facing and one side of said stiffening member, substantially as and for the purposes set forth. 95

4. A girth for harness comprising a concavo-convex stiffening member, said stiffening member being bounded by marginal edge-portions of a sinuous configuration, so as to form a forwardly extending central portion, and a rearwardly extending curved portion at each side of said central portion, said rearwardly extending curved portions terminating in end-members, and a casing of a soft and flexible material of a corresponding marginal configuration surrounding the said stiffening member, substantially as and for the purposes set forth. 100

5. A girth for harness comprising a concavo-convex stiffening member, said stiffening member being bounded by marginal edge-portions of a sinuous configuration, so as to form a forwardly extending central portion, and a rearwardly extending curved portion at each side of said central portion, said rearwardly extending curved portions terminating in end-members, and a casing of a soft and flexible material of a corresponding marginal configuration surrounding the said stiffening member, said casing comprising an outer and an inner facing, and a padding between said inner facing and one 115

side of said stiffening member, substantially as and for the purposes set forth.

6. A girth for harness comprising a concavo-convex stiffening member, said stiffening member being bounded by marginal edge-portions of a sinuous configuration, so as to form a forwardly extending central portion, and a rearwardly extending curved portion at each side of said central portion, 10 said rearwardly extending curved portions terminating in end-members, and a casing of a soft and flexible material of a corresponding marginal configuration surrounding the said stiffening member, and buckles at the 15 respective ends of said casing for attachment thereto of the ends of the saddle-straps, substantially as and for the purposes set forth.

7. A girth for harness comprising a concavo-convex stiffening member, said stiffening member being bounded by marginal edge-portions of a sinuous configuration, so as to form a forwardly extending central portion, and a rearwardly extending curved 25 portion at each side of said central portion, said rearwardly extending curved portions terminating in end-members, and a casing of a soft and flexible material of a corresponding marginal configuration surrounding the 30 said stiffening member, and buckles at the respective ends of said casing for attachment thereto of the ends of the saddle-straps, said casing comprising an outer and an inner facing, and a padding between said 35 inner facing and one side of said stiffening member, substantially as and for the purposes set forth.

8. A girth for harness comprising a concavo-convex stiffening member, and a casing 40 of a soft and flexible material surrounding said stiffening member, said casing comprising an outer and an inner facing, and a padding between said inner facing and one side of said stiffening member, loops extending from the outer facing, and a running strap extending through the said loops, substantially as and for the purposes set forth.

9. A girth for harness comprising a concavo-convex stiffening member, and a casing 50 of a soft and flexible material surrounding said stiffening member, and buckles at the respective ends of said casing for attachment thereto of the ends of the saddle-straps, loops extending from the outer facing, and a running strap extending through the said loops, substantially as and for the purposes set forth.

10. A girth for harness comprising a concavo-convex stiffening member, and a casing 60 of a soft and flexible material surrounding said stiffening member, and buckles at the respective ends of said casing for attachment thereto of the ends of the saddle-straps, said casing comprising an outer and an inner

facing, and a padding between said inner 65 facing and one side of said stiffening member, loops extending from the outer facing, and a running strap extending through the said loops, substantially as and for the purposes set forth.

11. A girth for harness comprising a concavo-convex stiffening member, said stiffening member being bounded by marginal edge-portions of a sinuous configuration, so as to form a forwardly extending central portion, 70 and a rearwardly extending curved portion at each side of said central portion, said rearwardly extending curved portions terminating in end-members, and a casing of a soft and flexible material of a corresponding 75 marginal configuration surrounding the said stiffening member, loops extending from the outer facing, and a running strap extending through the said loops, substantially as and for the purposes set forth.

12. A girth for harness comprising a concavo-convex stiffening member, said stiffening member being bounded by marginal edge-portions of a sinuous configuration, so as to form a forwardly extending central portion, 80 and a rearwardly extending curved portion at each side of said central portion, said rearwardly extending curved portions terminating in end-members, and a casing of a soft and flexible material of a corresponding marginal configuration surrounding the 85 said stiffening member, loops extending from the outer facing, and a running strap extending through the said loops, substantially as and for the purposes set forth.

13. A girth for harness comprising a concavo-convex stiffening member, said stiffening member being bounded by marginal edge-portions of a sinuous configuration, so as to form a rearwardly extending central portion, and a rearwardly extending curved portion 90 at each side of said central portion, said rearwardly extending curved portions terminating in end-members, and a casing of a soft and flexible material of a corresponding 95 marginal configuration surrounding the said stiffening member, said casing comprising an outer and an inner facing, and a padding between said inner facing and one side of said stiffening member, loops extending from the 100 outer facing, and a running strap extending through the said loops, substantially as and for the purposes set forth.

14. A girth for harness comprising a concavo-convex stiffening member, said stiffening member being bounded by marginal edge-portions of a sinuous configuration, so as to form a rearwardly extending central portion, and a rearwardly extending curved portion 105 at each side of said central portion, said rearwardly extending curved portions terminating in end-members, and a casing of a soft and flexible material of a corresponding marginal configuration surrounding the 110 said stiffening member, and buckles at the respective ends of said casing for attachment thereto of the ends of the saddle-straps, loops extending from the outer facing, and a running strap extending through the said loops, substantially as and for the purposes set forth.

15. A girth for harness comprising a concavo-convex stiffening member, said stiffening member being bounded by marginal edge-portions of a sinuous configuration, so as to form a forwardly extending central portion, 115 and a rearwardly extending curved portion at each side of said central portion, said rearwardly extending curved portions terminat-

ing in end-members, and a casing of a soft and flexible material of a corresponding marginal configuration surrounding the said stiffening member, and buckles at the respective 5 ends of said casing for attachment thereto of the ends of the saddle-straps, said casing comprising an outer and an inner facing, and a padding between said inner facing and one side of said stiffening member, loops extending 10 from the outer facing, and a running

strap extending through the said loops, substantially as and for the purposes set forth.

In testimony that I claim the invention set forth above I have hereunto set my hand this 18th day of September, 1908.

ANDREW NICOLL.
